UNITED STATES PATENT OFFICE.

GEORGE E. GOUCHER, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,113, dated August 1, 1882.

Application filed June 16, 1882. Term of patent 14 years.

To all whom it may concern:

Be it known that I, GEORGE E. GOUCHER, of the city of Philadelphia, State of Pennsylvania, have invented and produced a new and original Design for Fringe, of which the following is a specification, reference being had to the accompanying drawing, forming part thereof.

The drawing represents in front elevation a fringe which illustrates my design, which design consists in a fringe having a heading, A, of any suitable kind, to which is attached at intervals chenille pendants B of substantially cylindrical contour. The pendants B are each longitudinally divided by two colors, and the division of each successive pendant longitudinally by color throughout a given number of series of pendants, as represented in the drawing, is such that in each successive pendant in such series one block of color decreases in length and the other block of color increases in length until the last pendant of such series is composed of two substantially equal blocks of color.

A number of series of pendants, as above 25 described, arranged in line form my design.

I do not confine myself to the use of any given colors in the same pendant, nor to the use of any given colors in adjoining pendants.

I claim—

A design for a fringe consisting of a heading and a number of series of chenille pendants, each successive pendant of each of such series being longitudinally divided by two blocks of different colors in such manner that 35 the two blocks of color in a given pendant of the series respectively increase and decrease in each successive pendant of said series, substantially as set forth.

In testimony whereof I have hereunto signed 40 my name this 10th day of June, A. D. 1882.

GEORGE E. GOUCHER.

In presence of—

W. C. STRAWBRIDGE,
J. BONSALL TAYLOR.
